UNITED STATES PATENT OFFICE.

ORVILLE M. DONALDSON, OF DETROIT, MICHIGAN, ASSIGNOR OF ONE-HALF TO JAMES W. WAYMAN, OF HIGHLAND PARK, MICHIGAN.

VAPORIZER.

1,321,608.

Specification of Letters Patent. Patented Nov. 11, 1919.

Application filed October 31, 1917. Serial No. 199,422.

To all whom it may concern:

Be it known that I, ORVILLE M. DONALDSON, a citizen of the United States, residing at Detroit, in the county of Wayne, State of Michigan, have invented a new and useful Improvement in Vaporizers, of which the following is a specification.

This invention relates to electrical heaters for insertion much like a gasket in the line between the carbureter and the intake valve of an internal combustion engine. The heater is ordinarily bolted between the carbureter and the manifold.

The invention has for its object a heater of this description of improved efficiency and economy in construction.

In the drawings.

Figure 1 is a side view of a portion of the carbureter and manifold.

Fig. 2 is a plan view of the heating member partly in section.

Fig. 3 is a cross section of the same.

Fig. 4 is a detail of a modified form.

The carbureter is designated *a*, the manifold *b* and the body of the gasket-like member *c*. The body of the gasket-like member has the usual bolt holes *d*, *d* and the center opening for the gases. In this center opening is located a spiral of ribbon nickel-chromium wire *e*. This furnishes the electrical heating element which is connected at its outside end with the single insulated binding post *f* and at its inner end is grounded by being in contact with the conducting cross pin *g*. This cross pin *g* not only serves to ground the heating element and thus do away with an extra binding post but it also serves the function of supporting the coil in its proper relation to the gasket-like body and the passage therethrough. This is effected by utilizing the pair of insulating tubes or sleeves *h* around the pin *g* and a plurality of tubular spacers *i* about this insulating sleeve *h*. These spacers serve to properly space the convolutions of the spiral heating element while the space between the two insulating sleeves *h* at the center of the pin *g* serves to allow the inner end of the heating element to come into contact and be held in contact with the cross pin *g* so as to complete the return circuit. By tightening the nuts *j* on the ends of the conducting pin *g* the spacers are packed and pinch the convolutions of the

spiral heating element, thereby securely holding the heating element in place.

In Fig. 4 a slightly modified form of construction is shown in the way of the zig-zagged supporting bar *k* with a pair of insulating tubes *l* of flat elliptical cross section. The convolutions of the spiral heating element are alternately passed above and below this supporting element and the zig-zag portion of the supporting element serves to give a spacing arrangement by reason of the tendency of the convolutions to reach the bottom of the V-like portions that they occupy. The inner end of the heating element is attached to the exposed center portion of the supporting element so as to complete the return through the body of the gasket, carbureter, etc., to the battery, (not shown).

What I claim is:

1. In a vaporizer for the purpose specified, a metal gasket-like body provided with a central opening, a spiral heating element contained in the central opening, and a suitably insulated cross pin for supporting the spiral heating element and to which the inner end of the spiral is connected to ground the same.

2. In a vaporizing device for the purpose specified, the combination of a metal gasket-like body provided with a central opening, a spiral heating element, an insulated binding post passing through the body to which one end of the spiral heating element is connected, and a cross pin serving both to support the convolutions of the spiral heating element and ground the other end of said element.

3. In a vaporizing device for the purpose specified, a metal gasket-like body provided with a central opening, an insulated binding post passing through the body, a heating element connected at one end of the binding post and disposed in the central opening in the form of a spiral, and a cross pin having insulating means thereon to space the convolutions of the spiral heating element and serving both to support the heating element and to act as a continuation of the circuit through the heating element.

4. In a vaporizing device for the purpose specified, the combination of a metal body provided with a central opening, an insulated binding post passing through the body, a spiral heating element disposed in the cen-

- tral opening and having one end connected to the binding post, a cross pin, an insulating medium about the cross pin except at the center, and a plurality of sleeve-like insulating spacers for spacing the convolutions of the spiral heating element, the inner end of the spiral heating element having an electrical contact with the metal portion of the cross pin, for the purpose specified.
- 5 6. In a vaporizer for the purpose specified, the combination of a gasket-like body provided with a central opening, a spiral heating element secured therein and having an outside end connected with a source of 10 electrical energy, and a supporting cross member for the heating element serving also as an electrical conductor from the inner end of the heating element spiral.
- 15 7. In a vaporizer, the combination of a solid metal gasket-like body, an insulated binding post passing through the metal gasket-like body and insulated therefrom, and a spiral heating element at one end attached to the binding post and at the other end grounded and supported solely by being 20 connected to the metal gasket-like body through this grounding connection.
- 25

In witness whereof, I have hereunto set my hand on the 22nd day of October, 1917.

ORVILLE M. DONALDSON.
